(57) **CLAIM**

The ornamental design for a brine tank, as shown and described.

DESCRIPTION

FIG. 1 is a front perspective view of a brine tank, showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and

FIG. 7 is a bottom plan view thereof.

FIG. 8 is a bottom perspective view of the lid portion of the brine tank of FIG. 1;

FIG. 9 is a front view thereof;

FIG. 10 is a back view thereof;

FIG. 11 is a left side view thereof;

FIG. 12 is a right side view thereof;

FIG. 13 is a top plan view thereof; and

FIG. 14 is a bottom plan view thereof.

FIG. 15 is a front perspective view of the body portion of the brine tank of FIG. 1;

FIG. 16 is a front view thereof;

FIG. 17 is a back view thereof;

FIG. 18 is a left side view thereof;

FIG. 19 is a right side view thereof;

FIG. 20 is a top plan view thereof; and

FIG. 21 is a bottom plan view thereof.

The broken lines and unshaded areas within the broken lines depict portions of the brine tank that form no part of the claimed design.

1 Claim, 16 Drawing Sheets
